UNITED STATES PATENT OFFICE.

GEORGE F. BLAKE, OF BELMONT, MASSACHUSETTS.

DUPLEX PUMPING-ENGINE.

SPECIFICATION forming part of Letters Patent No. 270,575, dated January 16, 1883.

Application filed October 11, 1882. (No model.)

To all whom it may concern:

Be it known that I, GEORGE F. BLAKE, of Belmont, county of Middlesex, State of Massachusetts, have invented an Improvement in Duplex Pumping-Engines, of which the following description, in connection with the accompanying drawings, is a specification.

My invention relating to steam-pumps is embodied in a duplex pumping-engine, comprising two similar engines and pump-cylinders, so coupled together that each engine actuates the steam-valve of the other engine.

The invention has for its object to simplify the construction of the valve-actuating mechanism, which consists of a slotted or forked valve-actuating lever belonging to each engine, it being actuated by the piston-rod thereof. The said valve-actuating levers for the two engines are each fixed upon one end of a rock-shaft, having upon its other end a crank connected by a link with a tappet, which has a sliding movement upon the valve-rod of the other engine, and alternately engages each of two valve-rod collars on the said valve-rod at either side of it, thus causing the valve-rod to accompany it in the last part of its movement caused by the oscillation of the actuating-lever near the end of the stroke of the piston. The two rock-shafts have their bearings in pedestals sustained upon the framework connecting the engine and pump cylinders, and have their axes in the same plane with the axes of the valve-rods. The crank upon one rock-shaft extends upward therefrom, and the link connecting it with the tappet is above the level of the corresponding valve-rod, while the crank upon the other rock-shaft extends downward, and the link is below the valve-rod; but the cross-heads, actuating-levers, rock-shafts, cranks, tappets, and valve-rods of the two engines are duplicates of one another, thus greatly simplifying the construction, while in all other duplex engines, so far as I am aware, the valve-actuating levers are of different length and different order, and the different parts of the valve-gear of the two engines not exact duplicates.

Figure 1 is a side elevation of a duplex pumping-engine embodying this invention, one of the steam-cylinders being shown in longitudi-

nal section; Fig. 2, a plan view thereof; Fig. 3, a transverse section, showing only the valve-actuating mechanism as viewed when looking toward the steam-cylinders; and Fig. 4, a perspective view of the engine and its valve-operating mechanism.

The two engine-cylinders A B may be of any usual construction, steam being admitted to them through the branched inlet-pipe *a* and exhausted through the branched eduction *6a* or exhaust pipe *b*, and the flow of the steam to and from the ends of the cylinders through the parts *c d* being controlled by the valves *e*, which may be of any suitable construction. The steam-cylinders are connected with the pump-cylinders, which are not shown, by suitable frame-work, shown in this instance as consisting of the rods *f f' f''*. The piston-rods *g g'* are connected with cross-heads *h h'*, provided with pins *i i'*, which enter the slots or forks *70* 2 of the valve-actuating levers *k k'*, the said pins *i i'* being provided with friction rolls or sleeves *i''*. The levers *k k'* are connected with rock-shafts *m m'*, having their bearings in pedestals *n n'*, that are sustained upon the frame-*75* rods *f f'*. The rock-shafts *m m'* each have bearings in both the pedestals, and they carry cranks *o o'*, respectively, the former extending from the rock-shaft on the same side as the lever *k'* and the latter on the opposite side to the lever *k*. The crank-pins *o o'* of the said cranks are connected by links *p p'* with the tappets *r r'*, which slide freely on the valve-*80* rods *t t'*, and alternately engage collars *t''*, adjustably connected with the said rods, as described in another application for Letters Patent filed herewith. The axes of the rock-shafts *m m'* are in the same plane with the axes of the valve-rods, so that by making the levers *k k'* of the same length and the cranks *o o'* of *85* the same length the valve-rod and valve of each engine will have the same amount of movement.

The pins *i* and *i'* are placed, one at the forward and the other at the rear end of the respective cross-heads, and the distance between the said pins when the cross-heads are in line with one another is equal to the distance between the rock-shafts *m m'*, so that the movement of each valve relative to the travel of *90* *95* *100*

the piston of the other engine is the same, provided that the collars t^2 have the same adjustment on the valve-rods. It will be seen that the position of the pins $i\ i'$ on the cross-heads 5 is the same, and that all the parts of the valve-actuating mechanism of the two engines that are designated by the same letter of reference with and without the accent-mark ('') are the exact duplicates of one another, and may be 10 made interchangeable, thus greatly simplifying their construction. The links $p\ p'$ differ only in length by an amount equal to the distance between the rock-shafts $m\ m'$.

By having the rock-shafts on a level or in 15 the same plane with the valve-rods the power is more directly transmitted than when a different arrangement is employed.

The pedestals $n\ n'$ are provided with guides $u\ u'$ for the valve-rods $t\ t'$.

20 I claim—

1. In a duplex engine, the piston-rods and the valve-actuating levers operated thereby, combined with the rock-shafts, cranks, tappets, and valve-rods for the two engines made in 25 exact duplicate, substantially as described.

2. In a duplex engine, the combination of the cross-heads, valve-actuating levers, and rock-shafts, with their supporting-pedestals, cranks, tappets, and valve-rods, the axes of the said valve-rods and rock-shafts being in 30 the same plane, substantially as and for the purpose described.

3. In a duplex pumping-engine, the combination of the connecting frame-work between the steam and pump cylinders and the pedestals supported thereon, with the valve-actuating levers and cranks, and the rock-shafts connected therewith, having their bearings in the said pedestals and the valve-rods and guides therefor sustained by the said pedestals, substantially as described.

In testimony whereof I have signed my name to this specification in the presence of two subscribing witnesses.

GEO. F. BLAKE.
